UNITED STATES PATENT OFFICE

2,505,943

VENETIAN BLIND

Robert Jean Charbonneau, Detroit, Mich.

Application November 25, 1946, Serial No. 712,143

2 Claims. (Cl. 160—178)

1

This invention relates to improvements in Venetian blinds.

The invention pertains particularly to improvements in a Venetian blind assembly whereby the blind may be readily installed or removed from its mounting over the window opening.

The object is to provide in a Venetian blind having a head rail assembly, a head rail proper which carries the tilting and operating mechanism and which is provided with a cover adapted to enclose the mechanism supported upon the head rail and which cover itself is adapted to be coupled with the head rail to be supported thereby and to be uncoupled therefrom through slidable endwise telescoping of the head rail and cover.

More particularly the head rail is provided along opposite edges with complementary lengthwise guide channels and the cover is provided with side walls having oppositely inturned bottom edges slidably receivable within the guide channels of the head rail to couple the head rail and cover together. The head rail assembly has a cover so constructed and so coupled therewith as to serve as a valance shield for the blind assembly.

The head rail assembly which includes the cover is supported at opposite ends upon suitable bracket assemblies and a meritorious feature is the provision of improved bracket supports adapted to readily receive the opposite ends of the head rail and cover.

More particularly each bracket support includes a pair of bracket sections, one of which is adapted to be attached to the window casing or jamb member and to receive the end of the head rail assembly to support the same. The other section is adapted to complete the first section and to be readily coupled therewith to completely enclose the end of the head rail assembly, to support the same, and to serve as a dust cover thereover.

Another meritorious feature is the provision in a head rail assembly of the character described of a tilt rail including a rod which is supported for oscillation and is provided with improved frictional brake means associated therewith and adapted to releasably retain the tilt rail in any adjusted position to which it has been tilted.

Other objects, advantages and meritorious features will more fully appear from the following description, appended claims and accompanying drawing wherein:

Fig. 1 illustrates a Venetian blind, embodying my invention, mounted in window opening.

2

Fig. 2 is a vertical sectional view taken on the line 2—2 of Fig. 1.

Fig. 3 is a vertical sectional view lengthwise through a portion of the head rail assembly.

5 Fig. 4 is a perspective of one end of the head rail and cover removed from the end bracket.

My invention is embodied in a Venetian blind which includes the usual blind slats, supported for raising and lowering below a head rail 10.

10 The blind slats 12 are carried by ribbons 14 which are attached to portions 16 of a tiltable rod 18, which rod is supported at opposite ends within brackets 20 for oscillation. The brackets 20 are attached to the head rail 10. Operating cords

15 22 are secured to the portion 16 of the tiltable rod to oscillate the rod first in one direction and then in another. In order to maintain the tiltable rod at adjusted tilted positions, a simple ex-

pansible spring brake 24 is freely mounted upon the rod 18 between one end bracket 20 and an enlarged portion 16 carried by the rod and rotatable therewith.

The mechanism for raising and lowering the blind slats is conventional and is shown as comprising the cord 26, which passes over rollers 28 mounted upon the head rail 10. A brake member

30 30 may be provided to maintain the lift cord at adjusted positions of elevation of the blind slats. Associated with the head rail 10 is a cover 32.

35 This cover is shown as extending lengthwise of the head rail and being in the form of an inverted U in cross section. It comprises a top wall and two side walls. The side walls have their lower margins inturned at 34 and form flanges which

36 are slidably receivable within guide channels 36 of the head rail. The head rail 10 is provided along its opposite edges with complementary guide channels 36 which are adapted to receive the flanges 34 of the side walls of the cover slidably lengthwise of the head rail. Through this

40 endwise telescoping movement it is possible to attach the cover to the head rail or to remove the head rail therefrom quickly and easily.

The head rail assembly is supported at opposite ends by a pair of bracket assemblies which are attached to the window casing or jamb member and the two bracket assemblies are similar.

Each bracket assembly includes two cooperating sections. One section is indicated at 38 and in-

45 cludes an end wall and three side walls. The side walls include a top wall 40, a bottom wall 42 and a back wall 44. In the drawing the end wall is shown as secured to a window jamb by screws 46. Should it be desired to secure the

50 bracket to the outside of the casing rather than

to the inside of the jamb, the back wall is provided with a pair of screw apertures 48 whereby the back wall may be secured by screws to the casing.

The front of this section is open as is apparent and the end of the head rail assembly may be moved bodily in or out this open side. To close the open side of the first section there is provided a second section which is indicated in the drawing as 50. This second section is U-shaped in cross section as shown in Fig. 2. It comprises an outer wall, a portion of which closes the open side of the section 38 and is disposed opposite and is complementary to the back wall 44 of the section 38. It comprises a pair of opposite short wall sections extending from the front wall section and which are adapted to in part overlie the top wall 40 and the bottom wall 42 of the first section as shown particularly in Fig. 2. This section 50 may be attached through the bottom wall 42 of the first section to the head rail 10 by a screw 52 as shown in Fig. 2.

In Fig. 3 the assembly is shown with the section 50 removed and it is evident that it would be simple to remove the head rail assembly directly outwards from the section of the bracket that was permanently attached to the window. It is apparent that through withdrawing the screw 52 and removing the section 50 from each bracket assembly the head rail assembly might be withdrawn from the two brackets to remove the blind from the window. In Fig. 4 the head rail assembly is shown with the cover partially withdrawn with respect to the head rail proper. It is also apparent that the cover 32 might be readily withdrawn lengthwise from the head rail to uncover the operating mechanism for repair or replacement of any part.

What I claim is:

1. In a Venetian blind assembly, a head rail having complementary guide channels extending lengthwise of its opposite edges, blind tilting mechanism supported thereupon, a cover of an inverted U shape in cross section having a top and opposite side walls supported upon the head rail, the side walls of the cover having their lower edges inturned toward each other and slidably receivable within the guide channels of the head rail to secure the cover thereto.

2. A Venetian blind assembly as defined in claim numbered 1 characterized in that a pair of end brackets are provided, exhibiting facing socket portions rectangular in cross-section and adapted to removably telescopically receive opposite ends of the head rail and its cover, each bracket having opposed wall portions adapted to engage the side walls of the cover when seated therein holding said side walls and their in-turned edges within the guide channels of the head rail.
